Primary Examiner — Jonathan J Han*Assistant Examiner* — Christen Pilar Brown(74) Attorney, Agent, or Firm — ArentFox Schiff LLP(57) CLAIM

The ornamental design for a slipper, as shown and described.

DESCRIPTION

FIG. 1 is a front left perspective view of a slipper showing my new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

FIGS. 1-7 include broken lines. The broken lines are for the purpose of illustrating portions of the slipper that form no part of the claimed design. Colors form no part of the claimed design.

1 Claim, 7 Drawing Sheets(56)
